UNITED STATES PATENT OFFICE.

NICHOLAS LOSNESS, OF LOS ANGELES, CALIFORNIA.

DESIGN FOR A FLAG STAND.

Application filed April 16, 1927. Serial No. 21,626. Term of patent 3½ years.

To all whom it may concern:

Be it known that I, NICHOLAS LOSNESS, a citizen of the United States, residing at Los Angeles, in the county of Los Angeles and State of California, have invented a new, original, and ornamental Design for Flag Stand, of which the following is a specification, reference being had to the accompanying drawing, forming part thereof.

In the drawing, the figure is a perspective view of my flag stand.

I claim:

The ornamental design for a flag stand, as shown.

NICHOLAS LOSNESS.
